UNITED STATES PATENT OFFICE

141,734

DESIGN FOR A GAME BOARD

Richard E. Collins, Omaha, Nebr., assignor of
one-half to Charles E. Stenicka, Jr., Omaha,
Nebr.

Application September 26, 1944, Serial No. 115,464

Term of patent 7 years

(Cl. D34—5)

To all whom it may concern:

Be it known that I, Richard E. Collins, a citizen of the United States, residing at 4504 Camden Avenue, Omaha, in the county of Douglas and State of Nebraska, have invented a new, original, and ornamental Design for Game Board, of which the following is a specification, reference being had to the accompanying drawing, forming part thereof.

Figure 1 is a top plan view of a game board showing my new design.

Figure 2 is a side view of the same.

I claim:

The ornamental design for a game board, as shown.

RICHARD E. COLLINS.
